COMBINED BAR, CHAIR AND SIDE TABLE UNIT

Stanley H. Skalka, Springfield, Va., and Melvin R. Jones,
Baltimore, Md., assignors to Victor Stanley, Inc.,
Dunkirk, Md.

Filed Mar. 20, 1972, Ser. No. 236,573

Term of patent 14 years

Int. Cl. D6—06

U.S. Cl. D6—4

Fig-1

FIG-5

FIG. 1 is a front perspective view of a combined bar, chair and side table unit in closed position;

FIG. 2 is a rear perspective view thereof;

FIG. 3 is a front perspective view of the unit in opened position;

FIG. 4 is a front elevational view of the unit as shown in FIG. 3; and

FIG. 5 is a perspective view of the unit as shown in FIG. 3 but wherein the chair is extended in the form of a lounge.

We claim:

The ornamental design for a combined bar, chair and side table unit, as shown and described.
